AUTOMATIC CENTRAL BUFFER COUPLING
FOR RAILWAY CARS

Stefan Torma, Budapest, Hungary

Application November 18, 1935, Serial No. 50,437
In Germany November 19, 1934

15 Claims. (Cl. 213—89)

This invention relates to an automatic coupling for railway cars and pertains particularly to that type of couplings in which two projections are arranged diagonally opposite each other and the 5 projections are provided to extend from a base surface of the body of the coupling.

The subject-matter of the invention is characterized by the feature that the upper surface of the lower projection and the lower surface of 10 the upper projection lie substantially in a plane of the draft or buffering transmission line. In other words these surfaces are arranged so as to be in alignment with the height of the draft line extending between the two cars to be coupled. 15 The invention is further directed to a railway coupling wherein the base surface of the coupling head is substantially perpendicular to the draft and buffer transmission line.

The advantages of such improvements reside in 20 the fact that the projections of the coupling head can be shortened so that the overall length of the coupling is small as compared to such devices of the prior art. In addition to such improvements the invention provides a coupling having a large range of engagement and the 25 angular adjustment of the coupling heads is permitted in substantial, vertical and horizontal directions.

The various novel features and objects of the 30 invention will be more apparent to those skilled in the art upon a consideration of the accompanying drawings and the following description wherein an exemplary embodiment of the invention is shown and described.

In the drawings:

Figure 1 is a perspective view illustrating a basic form of one-half of the coupling.

Figure 2 is a view similar to Fig. 1 illustrating the fundamental form of the other half of the 40 coupling.

Figure 3 is a side view of the coupling halves illustrating an angular engagement thereof.

Figure 4 is a side view of the draw-hook illustrating the housing thereof in section.

Figure 5 is a side view partially in vertical section illustrating the details of the coupling wherein the section thereof is taken on the line V—V of Figure 6.

Figure 6 is a horizontal sectional view taken 50 on the line VI—VI of Figure 5.

Figure 7 is a vertical sectional view taken on the line VII—VII of Figure 5.

Figure 8 is a front end view of the coupling head.

Figures 9a—9d are vertical sectional views taken

on the line IX—IX of Figure 5 and illustrate means for locking the lifted draft transmission member.

Referring to the drawings and particularly Figures 1 and 2, the numeral 2 designates one 5 of the coupling heads and the other of the coupling heads is indicated generally at 1. The coupling head 2 comprises a body portion which is provided with two projections 3 and 4 extending forwardly from the body thereof and arranged diagonally opposite to each other. The projection 3 is formed by the surfaces 5, 6 and 7 which are more clearly illustrated in Figure 8. The projection 4 is bounded by the surfaces 8, 9 and 10 as shown in Figures 1 and 8. The general overall shape of the projections may be regarded as rectangular and having the surface 6 for example extend perpendicular or substantially so from the surface 10. The edges 11, 12, 13 and 14 as indicated by the heavy lines 20 in Figure 1 are preferably cut away to provide oblique surfaces or angular corners along these edges so that the ends of the projections will take the shape of that illustrated in Figure 8.

The coupling head 1 is also provided with projections 3 and 4 which are located so as to enter the cavities formed by the projections of the coupling head 2 when the two coupling heads are moved towards each other. In other words the staggered projections of the coupling heads 1 and 2 may be moved towards each other until the vertical surfaces of both heads are moved into engagement with each other. The vertical surfaces 5 and 8 are provided for the purpose of transmitting the buffering or pushing forces and 35 act in conjunction with the vertical surfaces 15 and 16 to provide means for pushing one coupling head before the other. The vertical surfaces 5, 8, 15 and 16 may be regarded as base surfaces and the term as used herein is intended 40 to relate to such parts of the coupling head.

The object of cutting away the edges 11, 12, 13 and 14 is for the purpose of causing the heads to be moved in an overlapping fashion even though one coupling head is not accurately positioned in the same axis as the other. The surfaces 6 and 7 as well as the surfaces 9 and 10 provide means for guiding the coupling heads after the preliminary engagement so that the vertical surfaces may be moved to a position immediately adjacent the base surfaces.

The line of intersection between the surfaces 6 and 7 and the line of intersection between the surfaces 9 and 10 lies in the geometrical longitudinal axis C—C as illustrated in Figure 1. 55

In a structural arrangement the line of intersection of the surfaces 6 and 7 does not lie in the line of intersection of the surfaces 9 and 10 as shown in Figure 8. These surfaces are shifted 5 slightly to the horizontal plane A—A and to the vertical central plane B—B so that the inter-engagement of the coupling heads is facilitated. Referring to Figure 3 there is illustrated in a side view the inter-engaged coupling head prior 10 to the completion of the coupling operation wherein the longitudinal axes of the coupling heads form an angle with each other. From an observation of Figure 3 it will be apparent that angular adjustment of the coupling heads will 15 be affected by the faces 5 and 15 when the coupling heads are moved further towards each other. When the coupling operation has been entirely completed the longitudinal axis C—C will lie in alignment with the draft and pressure transmitting line M—M.

The means for providing a draft connection between the coupling heads is shown in Figure 4 and comprises a hook 17 which is attached to the coupling head 1 by means of a transversely extending shaft or pivot 18. The axis of the shaft 18 crosses the central line M—M as illustrated in Figure 6. The inner hooked face of the draw-hook is provided with a sloping surface for engagement with the edge 19 of the opening 22. 25 The slope of the engaging portion of the hook is such that a line extending at right angles thereto and passing through the opening engaging point 19 will pass through the axis of the pivot 18. Thus the draw-hook cannot unintentionally be 30 come disengaged from engagement with the coupling head 2 under the action of the tractive power.

When the railway cars provided with such a coupling are moving over the tracks the coupling 40 heads will perform movements with respect to each other in the directions indicated by the arrow 20 of Figure 4 and the extent of these movements will depend upon the play between the coupling heads. When these movements take 45 place the draw-hook 17 will follow the coupling head 2 partly because of the mass or weight thereof and partly by reason of the friction arising at the point where the hook engages the aperture edge 19. Thus the hook 17 is caused to remain in engagement with the opening of the 50 coupling head 2.

The preceding description of the invention including the references to the drawings relates principally to the basic features of the invention 55 and Figures 5 to 9d pertain to a constructional embodiment of the coupling including the details thereof.

Referring particularly to Figure 5 it is to be noted that the coupling head 2 when engaged by 60 the hook 17 will turn the hook upwardly until the aperture 22 arrives below the free end of the hook when the hooked end thereof will drop into the opening under the influence of the weight thereof. In this position the abutment member 65 21 of the hook 17 will engage the upper surface of the coupling 2 in front of the aperture 22 to provide a proper position for the hook 17. When the parts of the coupling are in such a position the coupling operation is complete.

70 In order to uncouple the arrangement and to disengage the hook 17 a lever or arm 23 is provided to extend outwardly from the housing or coupling head as illustrated in Figure 6. A chain 75 24 may be provided on the end of the arm 23 so that movement of the lever 23 by means of the

chain in the direction of arrow 25 (Figure 7) will cause the lever to be pivoted about the shaft 23a. Such movement of the lever will cause the pressure bar 26 to engage the lug 27 which extends rearwardly from the draw-hook 17. Thus 5 the downward movement of the lug 27 will cause the hook 17 to be rotated about the pivot 18 and permit the hooked end to escape from the aperture 22. Arranged below the draw-hook and to one side thereof is a counter-pawl 29 from which 10 an arm 28 laterally extends to a position below the lug 27. The counter-pawl is rotatably supported on the shaft 18. When the hook 17 is being lifted out of the aperture 22 a similar hook 15 is lifted out of a corresponding aperture in the coupling head 1 by means of the pawl 29 which acts in an upward direction. When both draw-hooks have escaped the openings of the coupling heads the disengaging or uncoupling operation is 20 complete and the cars can thereafter be removed from each other.

The tip of the draw-hook as well as the openings for receiving the hooked end of the draw-hook are preferably provided with oblique or sloping surfaces 30 and 31 as shown in Figure 4. 25 The provision of such surfaces on these parts is not essential for lifting each draw-hook out of the coupling head but such surface arrangements are provided so that when the hook is partially lifted out of the opening 22 the pulling force exerted 30 on the hook 17 will cause the tapering surface 30 to ride on the oblique surface 31 and thus lift the hook automatically to completely disengage the same from the coupling head 2. The turning movement of the hook 17 on the shaft 18 rotates 35 the counter-pawl 29 which lifts the draw-hook of the other coupling head and permits it to escape from a similar opening 22 in the coupling head 1. Rotation of the hook on the shaft 18 as shown in Figure 5 in a clockwise direction will cause a 40 part of the lug 27 to engage the arm 28 and thus lift the tip portion of the pawl 29. The purpose of the sloping surfaces 30 and 31 is thus to provide means for preventing a situation from arising in which only one draw-hook is subjected to the 45 action of the tractive power.

As a result of possible inaccuracies in the shape of the various parts of the coupling and particularly the draw-hooks it is practically impossible to arrange the hooks so that both hooks will engage the respective apertures 22 simultaneously along the entire breadth of each hook. Accordingly the inner face of each draw-hook is formed to have a convex shape as indicated at 32 and shown in the dotted lines of Figure 6. Thus it is 55 possible for each hook to properly engage the edge of the openings 22 without subjecting the hooks to a twisting action as a result of one edge engaging the openings 22.

The edge of the openings 22 is preferably provided with a convex profile so that the hooks 17 may be more readily removed from engagement therein. The edge surfaces of the openings and the engaging surfaces of the hooks may be formed of hardened material and thus the strain on these 65 surfaces may be maintained within satisfactory limits even though the surfaces are subjected to wear at only one point. Referring to Figure 5 it is to be noted that a spring 34 is interposed between the arm 28 and the sleeve rotated by the 70 lever 23 and this spring acts to cause the hook 17 and the pawl 29 including the lever 23 to remain in their proper respective positions with respect to each other regardless of the vibrations taking place while the car or cars are moving over the 75

railway tracks. If one of the springs housed in each of the coupling heads is broken the other spring will nevertheless act for fulfilling the purposes of the broken spring.

5 The invention includes means for locking the lifted draft transmission member or hook 17 and such mechanism is provided so as to render it unnecessary to hold the chain 24 until the coupling heads have actually been withdrawn from 10 one another. Such a mechanism is in various stages of operation illustrated in Figures 9a-9d. The mechanism comprises a key 36 having the lower end 37 thereof pointed and adapted to engage the upper surface of the lower projection 15 extending from the opposite coupling head. During the uncoupling operation the chain 24 is manually pulled so that the lever 23 is rotated about the shaft 23a and the sleeve rigidly fixed thereto carries a cam 38 which will be turned in the direction of the arrow shown in Figure 9a. During such movement the cam 38 will engage the key 36 and turn it in an angular position as illustrated in Figure 9b. During such movement of the lever 23 the hook 17 will be lifted so as to be removed 20 from engagement with the opposite coupling head. Further turning of the lever 23 will permit the cam 38 to slip over the end of the key 36 as shown in Figure 9c. The key 36 will therefore return to its original position which movement may be 25 assisted by a weight 39. In this position the cam 38 rests upon the upper end of the key 36 so as to prevent counterclockwise movement of the cam 38 and the draw-hook 17 as long as the opposite coupling half by which the key is supported has 30 not been completely withdrawn from the coupling head 1. Thus it is not necessary to maintain tension on the chain 24 until the cars or coupling heads have been completely withdrawn from one another. When the coupling head 2 has been 35 completely withdrawn from the coupling head 1 the key 36 will fall as a result of its weight and as a result of the action of the spring 34. The mechanism will then be in a position as shown in Figure 9d which represents the complete uncoupled position. In such a stage of operation 40 all members of the locking member return to a position of rest by reason of their weight and by means of the spring 34. Accordingly the hooked end of the draw-hook moves downwardly so that the lug 27 extending from the rear thereof engages the pressure bar 26 whereby further downward swinging of the hooked end is prevented.

Such a coupling head may be attached to a railway car in various manners. An advantageous 55 arrangement is illustrated in Figure 5. Such an arrangement comprises a hollow draft-bar 41 which extends from the railway car and which is intended to withstand the pushing and pulling forces applied thereto. The coupling head is attached to the draw-bar 41 by means of a bolt and a washer 42 in such a manner that the coupling head can swing within predetermined limits in all directions. The weight of the coupling head is preferably supported by means of spring (not shown). The buffing or pushing forces are transmitted from the coupling head to the draw-bar 41 by means of the curved surface appearing at the end of the radius R. The tractive or pulling forces are transmitted from the coupling head or draw-bar 41 by means of a bolt or the washer or collar 42. The collar 42 and the shouldered end of the draw-bar 41 are provided with curved surfaces having a radius r. By suitable selection of the radius R and the radius r the friction arising 70 at the various curved surfaces may be maintained

so as to prevent detrimental movement of the coupling head with respect to the draw-bar. Such relative movements however are necessary particularly when the center line of the inter-engaging coupling heads do not lie exactly at the same 5 height which may be caused for example by one car being loaded to a greater extent than the other. The pushing or impact forces arising from such a case would tend to lift the lighter loaded car so that derailments of the car having the 10 higher draft center line might be caused in negotiating curves of the track. Theoretically the car having the lower transmission center line will not lift the other car if the difference between the height of the two draft center lines is: 15

$$h \geq 2R\mu$$

where μ indicates the coefficient of friction arising between the curved surfaces having the radius R. The capacity of the angular adjustment is 20 favorably influenced not only by the symmetric arrangement of the projections 3 and 4 but also by the short length l of the head 1 as shown in Figure 3. This fact can readily be ascertained by tracing the coupling heads 1 and 2 at several differences of height of the cars. Accordingly it is important to make the coupling heads short. In Figures 1 and 2 it is to be noted that the engaging surfaces and the buffing surfaces or the angle adjusting surfaces are so designed that the coupling head is as short as possible. The other members of the coupling heads are so designed and arranged that the projections 3 and 4 need not be elongated. It is much more advantageous 25 to arrange the hook 17 or the member transmitting the pulling force in the horizontal middle plane of the coupling instead of positioning such means in the vertical middle plane. From an observation of Figure 1 it may be seen that the distance a is greater than the distance b and such an 30 arrangement is provided since the difference in height to be compensated for between two opposite coupling heads is generally smaller than the lateral difference. It is for this reason also that the edges 12 and 14 are cut away to a smaller extent than the edges 11 and 13. Thus there is provided sufficient space for the tractive power transmitting member or the hook 17 within the extent 35 of the coupling head so that the projections need not be elongated. Elongation of the projections however would be necessary if the tractive power transmitting member were housed in that part 40 of the head which has the length b. According to the present improvement the two hooks 17 are loaded only with one-half of the tractive power 45 and the size of these elements may be small and thus housed in a relatively small space. 50

The draw-hook as above described constitutes the means for transmitting the pulling force and the nose of the hook is broad and can therefore 55 be made short and still sufficiently strong. The draw-hook transmits the tractive power to the coupling heads by means of the shaft 18 provided in the rear part of the coupling head. The upper of the two projections is thus relieved from the action of the tractive force. It is not necessary to make the upper projections stronger or longer as would be necessary if the element transmitting the tractive power would be a shiftable bolt or the like. Furthermore, the draw-hook 60 designed in accordance with the present invention can be more easily disconnected than would be possible with the use of a shiftable bolt. 65

The key 36 described in the mechanism shown in Figures 9a-9d is arranged in the long surface a 70 75

of the coupling head so that the cars can move away from one another for a certain distance without the coupling heads assuming a state of operation in which they are ready for the next coupling operation. Such a feature is of importance in shifting or shunting railway cars. If the key 36 were supported in a position by the short portion *b* it might be possible to couple cars unintentionally since the time required for un-

10 coupling cars in shunting would be insufficient to render the coupling head operable for the next coupling operation.

The symmetric and short design of the coupling heads is advantageous not only with respect to the angular adjustment of the two coupling heads but also provides an additional improvement in that the necessary pipes and cables which pass from one car to the other can be attached to the sides of the coupling more easily than with the devices heretofore known. Still another advantage is provided by the coupling in that it will operate satisfactorily without springs since each of the movable parts is capable of assuming a proper position by reason of its own weight.

15 Although certain preferred embodiments of the invention have been described it is apparent that modifications may be made therein by those skilled in the art. Such modifications may be made without departing from the spirit and scope 20 of the invention as set forth in the appended claims.

I claim:

1. Automatic central buffer coupling for railway cars comprising, a coupler head having two 35 diametrically arranged projections, the inner surface of each projection comprising three surfaces arranged substantially perpendicular to one another and connected by two intersecting oblique plane surfaces while the transmission of the tractive force takes place at two points in the horizontal central plane, and the two points transmitting the tractive force being opposite each other with respect to a line in said plane which connects together the draft bar joint point 40 of the coupling, and the point of intersection of the extension of the said three surfaces which are arranged substantially perpendicular to one another.

2. A coupling as specified in claim 1, characterized by the feature, that of the three surfaces 50 arranged substantially perpendicular to one another the intersection line of two of said three surfaces lies substantially in the central draft and buffering transmission line.

3. A coupling as specified in claim 1, characterized by the features, that of the three surfaces arranged substantially perpendicular to one another, two of said surfaces form an inner horizontal edge and two of said surfaces form an 55 inner vertical edge and that said interior edges are cut off by said oblique surfaces.

4. A coupling as specified in claim 1, characterized by the features, that of the surfaces arranged substantially vertical to one another, two 60 of said surfaces form an inner horizontal edge and two of said surfaces form an inner vertical edge, that the said interior edges of said projections are cut off by said oblique surfaces and that said oblique surfaces cut away the vertical inner 65 edges of said projections in a higher degree than the horizontal edges of said projections.

5. A coupling as specified in claim 1, characterized by the features, that of the three surfaces arranged substantially perpendicular to one another, two of said surfaces form an inner hor-

izontal edge and two of said surfaces form an inner vertical edge and that said interior edges are cut off by said oblique surfaces, one oblique surface being parallel to a horizontal transverse line and extending substantially up to the horizontal 5 middle plane and the other oblique surface extending in a vertical plane substantially up to the transverse vertical middle plane of the coupling head.

6. A coupling as specified in claim 1, characterized by the feature, that a draft transmission member rotatable about a bolt is arranged within the profile of the coupling head in such a manner that it extends substantially through the horizontal middle plane of the coupling 15 head.

7. A coupling as specified in claim 1, characterized by the features that in the first projection a draw hook rotatable parallelly to the vertical middle plane is arranged and that in 20 the second projection a recess for the reception of the draw hook of the opposite coupling head is provided.

8. A coupling as specified in claim 1, characterized by the features that a draw hook is arranged in the upper projection and that a nose of said draw hook projects out of said upper projection through a recess provided at the horizontal transition surface between the vertical buffering surfaces, whereas another recess is provided at the diagonally opposite lower projection likewise at the horizontal transition surface between the vertical buffering surfaces there located so that the draw-hook of the oppositely located coupling head can engage said recess of the lower 35 projection while the coupling procedure is going on.

9. A coupling as specified in claim 1, characterized by the feature that a draw hook is arranged in the upper projection and that the hook 40 surface of the draw-hook is so designed that an imaginary line extending perpendicular from any engaging point of the engaging hook surface intersects approximately the axial line of the pivot of the draw-hook.

10. A coupling as specified in claim 1, characterized by the feature that a draw hook is arranged in the upper projection and that the engaging surface at the nose of the draw-hook is convex.

11. A coupling as specified in claim 1, characterized by the feature that a draw-hook is arranged in the upper projection and a recess for the reception of the corresponding hook of a cooperating coupler head is arranged in the lower 55 projection and that said recess has a convex surface engaged by the hook surface of the corresponding hook of the cooperating coupler head.

12. A coupling as specified in claim 1, characterized by the features that a draw-hook is arranged in the upper projection and that a counter pawl is turnable in the lower projection, said counter pawl having a lateral arm, and that a lug is arranged on the draw-hook in the upper projection, said lug being adapted to strike the arm on the counter pawl and to lift said counter-pawl when the draw hook is lifted, so that the counter-pawl lifts simultaneously the draw-hook of the opposite coupling head.

13. A coupling as specified in claim 1, characterized by the features that the upper projection contains a draw-hook and a device for lifting the draw-hook of the opposite head, said device consisting of a lever adapted to be rotated by hand, a shaft fixed to said lever, a second 75

- lever on said shaft, a lug on the draw-hook and a pressure bar between said second lever and said lug, said bar adapted to push down said lug and to lift said draw-hook, a counter pawl rotatable in the lower projection, said counter pawl having a lateral arm extending up to the under side of said lug of the draw-hook, said lug being adapted to strike the arm on the counter pawl to lift the counter-pawl and corresponding draw-hook of a cooperating coupler head, a lateral lug arranged on said shaft, and a spring connecting said lateral lug to the free end of the lateral arm of the counter pawl and said spring normally holding said counter pawl down.
- 15 14. A coupling as specified in claim 1, characterized by the features, that one projection contains a draw hook and a device for lifting said draw hook, a device for blocking the lifted draw hook arranged in said projection and said 20 device having a key adapted to abut on the lower projection of a cooperating coupler head and to hold the device in its locking position when the coupling heads are interengaged.
15. A coupling as specified in claim 1, characterized by the features, that one projection contains a draw hook and a device for lifting the draw hook, a device for locking the lifted draw hook arranged in said projection and said device having a weighted key adapted to abut on the lower projection of a cooperating coupler head and to hold the device in its locking position when the coupler heads are interengaged, the device for lifting the draw hook having a cam adapted to turn said key into an oblique position and to slip over and rest upon said key after the return of said key to its normal vertical position so that said key locks the lifted draw hook as long as the coupler heads are interengaged.

STEFAN TORMA. 20
